UNITED STATES PATENT OFFICE.

FRANK D. WHITE, OF PROVIDENCE, RHODE ISLAND, ASSIGNOR OF ONE-HALF TO ALEXANDER M. CHADBOURNE, OF PROVIDENCE, RHODE ISLAND, AND ONE-HALF TO GEORGE G. WHEELER, OF CRANSTON, RHODE ISLAND.

COMBINED CIGAR HOLDER AND PIERCER.

1,263,977.

Specification of Letters Patent. Patented Apr. 23, 1918.

Application filed November 10, 1917. Serial No. 201,204.

To all whom it may concern:

Be it known that I, FRANK D. WHITE, a citizen of the United States, and resident of the city of Providence, in the county of Providence and State of Rhode Island, have invented certain new and useful Improvements in Combined Cigar Holders and Piercers, of which the following is a specification.

10 This invention relates to a combined cigar holder and piercer, and has for its object to provide a cigar holder having a piercing member therein, which is adapted to pierce and enter the end of a cigar when the latter is placed in the holder for the purpose of causing the cigar to draw freely when smoked.

With these and other objects in view, the invention consists of certain novel features 20 of construction, as will be more fully described, and particularly pointed out in the appended claim.

In the accompanying drawings:

Figure 1— is a sectional elevation of my 25 improved holder illustrating a cigar in dotted lines as retained therein.

Fig. 2— is a perspective view showing the stem of the holder with the piercer projecting therefrom and the bowl portion removed.

Fig. 3— is a perspective view of the bowl portion of the holder.

Referring to the drawings, 10 designates the stem portion of the holder, which may 35 be made of any suitable material, the same being made hollow or with a longitudinally-disposed opening 11 therethrough, through which the smoke may be drawn from the cigar into the mouth of the smoker.

40 The outer end of this stem is provided with a barrel portion 12 onto which one end 13 of the bowl portion 14 of the holder is fitted.

The essential feature of my invention is 45 the provision of a piercing member 15 which is connected to the stem 10 in any suitable way, but I preferably form this piercing member of a thin blade of metal having a

body portion 16 and a head portion 17, the head portion being preferably larger, wider 50 or of greater cross-sectional area than the body portion, for two reasons. First, so as to form a hole in the end of the cigar, a little larger than the body portion of the piercer, to permit a free draft through the 55 cigar along the smaller sized body portion; and second, by enlarging the head portion it assists in retaining the cigar in the holder. The outer end of the stem is provided with a transverse slot in which the end of the 60 thin blade is fixed.

It is found in practice that by providing a longitudinal opening 18 through the blade which connects with the hole 11 in the stem, that when the piercer enters the end of the 65 cigar, the tobacco leaves are spread and separated and are retained slightly opened up so as to permit the smoke to draw freely through this opening 18 in the blade.

I have shown and described a blade form 70 of piercing member with a hollow center portion, but I do not wish to be restricted to this particular form of piercing member as any other form of piercer which is mounted within the bowl to enter the end 75 of the cigar when positioned in the holder, will fall within the spirit of my invention, the scope of which is limited only by the terms of the appended claim.

I claim:

A combined cigar holder and piercer comprising a hollow stem member slotted across its end, a thin, flat blade having a longitudinally-disposed opening through its middle portion extending from one end nearly 85 the length thereof, the open end of said blade being fixed in the slot in the end of said stem with its opening registering with that in said stem, and a bowl member mounted on said stem and readily removable therefrom.

In testimony whereof I affix my signature.

FRANK D. WHITE.

Witness:

HOWARD E. BARLOW.
